CLAIM

The ornamental design for a hand fishing reel with internal storage for tackle, as substantially shown and described.

DESCRIPTION

FIG. 1 is a right side elevation view of the hand fishing reel with internal storage for tackle of the present invention, with the cap shown in place, the left side elevation view being a mirror image thereof;

FIG. 2 is a cross sectional view shown along line 2-2 of FIG. 1;

FIG. 3 is a right side elevation view with the cap shown removed, the left side elevation view being a mirror image thereof;

FIG. 4 is a front elevation view, with the cap shown in place; FIG. 5 is a front elevation view, with the cap shown removed;

FIG. 6 is a rear elevation view;

FIG. 7 is a front elevation view of the cap;

FIG. 8 is a rear elevation view of the cap; and,

FIG. 9 is a top plan view, with the cap shown in place, the bottom plan view being a mirror image thereof.

Broken and dotted lines in the Figures are for the purpose of illustrating portions of the hand fishing reel with internal storage for tackle and form no part of the claimed design.
